(57) **CLAIM**

The ornamental design for an evaporator assembly, as shown and described.

DESCRIPTION

FIG. 1 is a front perspective view of an evaporator assembly showing our new design;

FIG. 2 is a top plan view of the evaporator assembly of FIG. 1;

FIG. 3 is a front elevation view of the evaporator assembly of FIG. 1;

FIG. 4 is a right elevation view of the evaporator assembly of FIG. 1;

FIG. 5 is a left elevation view of the evaporator assembly of FIG. 1;

FIG. 6 is a rear elevation view of the evaporator assembly of FIG. 1; and,

FIG. 7 is a bottom plan view of the evaporator assembly of FIG. 1.
